UNITED STATES PATENT OFFICE

153,466

DESIGN FOR A PANEL TYPE DELIVERY TRUCK

Clifford Brooks Stevens, Milwaukee, Wis., assignor to Omar Incorporated, Omaha, Nebr., a corporation of Delaware

Application November 28, 1947, Serial No. 142,853

Term of patent 14 years

(Cl. D14—3)

To all whom it may concern:

Be it known that I, Clifford Brooks Stevens, a citizen of the United States, residing at Milwaukee, in the county of Milwaukee and State of Wisconsin, have invented a new, original, and ornamental Design for Panel Type Delivery Truck, of which the following is a specification, reference being had to the accompanying drawings, forming part thereof.

Figure 1 is a perspective view showing the front right side and top of a panel type delivery truck showing my new design;

Figure 2 is a top view thereof;

Figure 3 is a side view illustrating the left side of the truck; and

Figure 4 is a rear view.

The dominant features of my design reside in those portions thereof illustrated in full lines.

I claim:

The ornamental design for a panel type delivery truck, as shown and described.

CLIFFORD BROOKS STEVENS.
